UNITED STATES PATENT OFFICE

2,170,784

APPARATUS FOR FLATTENING LEAD WIRES

John F. Donovan, East Cleveland, and John Flaws, Jr., Cleveland Heights, Ohio, assignors to General Electric Company, a corporation of New York

Application November 13, 1937, Serial No. 174,416

8 Claims. (Cl. 29—34)

Our invention relates to methods and apparatus for making leading-in wires for incandescent lamps and other like devices, and more particularly our invention relates to a method and apparatus for preparing and flattening the portion of the leading-in wire which is subsequently sealed into a vitreous portion of the hermetically sealed enclosure of said devices.

In providing a suitable conductor for this purpose, the sealing portion thereof must have either the same coefficient of expansion as the vitreous portion of the device in which it is sealed or must be of such a shape as to yield to the unlike expansion of the vitreous portion and still remain hermetically sealed thereto. The most desirable way of constructing the leading-in wire so that it functions according to the latter method is to flatten the sealing portion to a very thin section. This type of leading-in wire is well known but little success has been experienced commercially with it because of the difficulty of consistently flattening the wire to exactly the size required. Heretofore the wire has been flattened by a single blow with apparatus which could not be made to operate absolutely uniformly and remain in adjustment for any appreciable length of time.

According to our invention, the leading-in wire is flattened by a multiplicity of relatively light blows or squeezing operations preferably produced by either a mechanical or a pneumatic hammer. This method is preferred because the striking surfaces do not become grooved by the wire and because of the simplicity of adjusting the apparatus and keeping it in adjustment. In combination with such apparatus, we provide means for removing some of the material from that portion of the wire which is to be flattened, for the dual purpose of removing any coating that may be on it and for reducing the size of said section so that it does not increase in width objectionably when flattened. The leading-in wire is preferably reduced in size by scraping apparatus. Other features and advantages of the method and apparatus of our invention will be apparent from the description which follows of one species thereof and from the accompanying drawings.

In the drawings, Fig. 1 is a perspective view of an apparatus comprising our invention; Fig. 2 is a section through the scraping portion of the apparatus; Fig. 3 is a section along line 3—3 of Fig. 2; Fig. 4 is a section along line 4—4 of Fig. 2; and Fig. 5 is a vertical section through the wire flattening portion of the apparatus.

Referring to Fig. 1, the wire 10 passes from

right to left through the apparatus and may consist, for example, of a copper wire having a coating of nickel thereon. The wire 10 is taken from a source of supply (not shown) which comprises a spool, means for keeping a relatively uniform tension in the wire as it is withdrawn and suitable straightening means. The said wire passes directly from the end of the rotary straightener 11 to the wire cleaning or scraping apparatus 12. From the scraping apparatus 12, which removes the nickel coating from that portion of the wire 10 that is to be flattened, said wire 10 passes through the feeding, flattening and severing apparatus 13, 14 and 15 respectively which advance the wire 10, flatten the previously cleaned portion thereof and sever it into lengths forming single leading-in wires. The operating period of each of these portions 12, 13, 14 and 15 of our apparatus is controlled by a plurality of cams (not shown) located on a common shaft below the table 16, and except for the feeding apparatus 13, occurs during the rest period of the wire 10 between longitudinal indexing movements thereof.

The wire 10 located in operating relation to the scraping apparatus lies as shown in Figs. 1, 2, 3 and 4 in the longitudinal groove 17 in the rod or shaft 18 and passes over the jaw 19, between the scraping knife 20 and the block 21 and between the jaws 22 and 23. The serrated end 19' of jaw 19 and jaws 22 and 23 close on the wire 10 immediately after it comes to rest following an indexing movement thereof and prevent the section of said wire 10 therebetween from being moved out of position by the scraping operation. The jaw 19 is pivoted on the pin 24 in the rod 18 and is moved so as to grip the wire 10 by the slide wedge 25 which is pushed against the tapered end 20' of said jaw 19. The sliding wedge 25, as shown in Fig. 3, is located in a key-stone-shaped groove in the rod 18 which prevents it from moving sideways, and is moved longitudinally into position by the lever 26 to which it is connected by the link 27. The lever 26 is pivoted on the pin 28 in the bracket 29 which also supports the rod 18 and is fastened to the bracket 30 on the table 16. Said lever 26 is connected by the link 31 to the lever 32 which is pivoted on the pin 33 extending from bracket 30. Said lever 32 is operated by a cam (not shown) located below the table 16 through the rod 34. The same movement of lever 32 which actuates jaw 19 causes the jaws 22 and 23 to close on the wire 10 as the stud 35 in the end of said lever 32, against which the slide 36 normally rests, is lowered so that said slide 36 moves down in the ways 55

in the bracket 37 to actuate the jaws 22 and 23 which are connected thereto through links 38 and 39. The jaws 22 and 23 are pivoted on pins 22' and 23' on the bracket 37 which is mounted on 5 the bracket 30 and which has ways therein for the slide 36 in which said slide is held by the plate 40. The spring 41 located between posts in the slide 36 and plate 40 contracts as the slide 36 moves down.

10 Now that the portion of the wire 10 in operative relation to the scraping apparatus 12 is held securely, the scraping knife 20 is brought down into engagement therewith and, while rotating rapidly about said wire 10, is moved back 15 and forth longitudinally with respect thereto. The knife 20 is mounted on the arm 42 which is pivoted on stud 43 at one end and has a yoke 43' at its opposite end which is engaged by the stud 44 extending from lever 45 which swings 20 said arm 42 back and forth to produce the scraping movement. The stud 43 is in two parts extending from opposite sides of a block 47 which in turn is mounted on a pin 48 pivoted in the yoke 49 and is turned, so as to raise and lower the 25 knife 20, by the collar 50 attached to the end thereof. As shown in Figs. 2 and 4, the collar 50 is turned by a pair of studs 51 extending from the cam 52 which is pivoted on the pin 48. The said cam 52 is pivoted by the rotation of disc 53 30 on which the yoke 49 is mounted, the said cam 52 being carried against a roller 54 on arm 55, so that the knife 20 is moved. During the period the knife 20 is raised above the wire 10, the cam 52 extends some distance beyond the periphery 35 of the disc 53. When the knife 20 is dropped onto the wire 10, the lever 55 is moved so that the roller 54 strikes the cam 52 during rotation of the disc 53 and the latch 56 moves into position behind the dog 57 on the cam 52. The lever 40 55 is pivoted on the bracket 30 and is operated by a cam (not shown) below the table 16 through the bar 58. The holes in the collar 50 are larger than the studs 51 engaging them so that the arm 42 is allowed sufficient free movement to cause 45 the knife 20 to engage the wire 10 properly while the cam 52 is held by the latch 56. The latch 56 is pivoted on the bolt 59 extending from the disc 53 and, when moved into position behind the dog 57, allows the spring 60, located between posts 50 in the disc 53 and the latch 56, to contract. The disc 53 is mounted on the hollow shaft or sleeve 61 which surrounds the rod 18 and is mounted in the ball bearings 62 and 63 within the bracket 30. The said shaft 61 is turned, so that the 55 knife 20 engages the entire periphery of the wire 10, by means (not shown) operating through the belt 64 and pulley 65. The movement of the knife 20 and arm 42 longitudinally of the wire, produced by the stud 44 and lever 45, is caused 60 by the movement of the roller 67 on one end of said lever 45 in and out of the hollows in cam 68 during the rotation of the disc 53. The lever 45 is pivoted on a pin 69 mounted on the disc 53 and the roller 67 thereon is always held in engagement 65 with the cam 68 by the compression spring 70 which butts against the disc 53 and the lever 45. The knife 20 engages the wire 10 with the contracting force of the spring 71 which extends between the arm 42 and a post extending 70 from the face of the disc 53 and cuts to a depth governed by the position of the roller 72 which engages the plate 73 on one side of the arm 42 when the limit is reached. The roller 72 is mounted on the yoke 74 which has a stud extending 75 ing therefrom through a hole in the block 75 at-

tached to the face of the disc 53, the said stud being held in position by the adjusting nuts 76 threaded thereon and engaging said block 75. The block 71 is mounted on the face of the disc 53 by means of the bracket 77 and is provided with raised portions at both ends as shown in Figs. 1 and 2 to prevent the wire 10 from being moved sideward out of position thereon by the 5 knife 20.

Following the cutting or scraping interval of 10 the knife 20, it is raised from the wire 10, and the jaws 19, 22 and 23 are moved so as to release their hold on said wire 10. The movement of the jaws 19, 22 and 23 is brought about by their operating means already described, whereas 15 the movement of the knife 20 is caused by the tripping of the latch 56 which allows the arm 42 and cam 52 to shift said knife. The latch 56 (Fig. 4) is tripped by movement of a roller 78 20 into the path of movement thereof created by the rotation of the disc 53 and is brought about 25 by the shifting of the lever 79 on which said roller 78 is mounted by a cam (not shown) located below the table 16 and acting through rod 80. The cam 52 and arm 42 are moved partially by 30 the centrifugal force created by the rotation of the disc 53 and partially by the leaf spring 81 mounted on the stud 82 extending from the disc 53 and engaging a stud 82' extending from the cam 52. The movement of the cam 52 is limited 35 by the length of the slot 83' therein in which the stud 83 extending from the disc 53 is located.

After treatment by the scraping apparatus, the wire 10 is drawn into the groove 84 in the slide 85 of the feeding apparatus 13 which operates intermittently between the operating periods of the scraping and flattening apparatus 12 and 14 respectively. The feeding operation is started by the right to left (Fig. 1) movement of the arm 86 mounted on a stud extending from the back of bracket 87, which movement is created by a cam (not shown) located below the table 16 and actuating said arm 86 through the rod 88 and the arm 89 also mounted on said stud. The arm 86 engages a roller on the end of an 40 arm 90 which is fastened to a pin 91 rotatably mounted in the slide 85 and causes the arm 90 to turn said pin 91 so that the block 92 is brought down against the wire 10 in the groove 84 therein to clamp said wire between said slide 85 and 45 block 92. The lower end of the block 92 is made smaller than the remainder so that it passes freely into the groove 84 in the slide 85. Following the clamping of the wire 10, the movement of the arm 86 causes the slide 85 to be shifted in 50 the ways in bracket 87 so that the wire 10 is advanced. This movement is continued until the wire 10 is advanced a distance equal to the length of the individual leading-in wire being manufactured and is followed by the return 55 movement of the arm 86 which first swings the block 92 up from the wire 10 to release it and then returns the slide 85 to its former position. During the return movement of the slide 85 the wire 10 remains stationary since it is then held 60 by the jaws 22 and 23 of the scraping apparatus 12 and has sufficient stiffness to resist buckling. 65

The wire 10 advanced beyond the feeding apparatus 13 passes through the opening in the guide tube 93, between the anvils 94 and 95 of 70 the flattening apparatus 14 and into the guide tube 96. The guide tubes 93 and 96 are mounted on the bracket 97 and direct the wire 10 across the center portions of the anvils 94 and 95. The anvil 94 is also mounted on the bracket 97 while 75

the anvil 95 is mounted on the air hammer 98. When the wire 10 comes to rest, air is admitted to the hammer 98 through the valve 99 (Fig. 5) located therebelow and the lower anvil 95 is driven upward against the wire 10 in a plurality of rapid and relatively light blows of sufficient force to gradually swage the wire 10 to the thickness desired. The air hammer 98 is a commercial product of The Chicago Pneumatic Tool Company, with offices in New York City, and is known as the type UU ring valve hammer delivering approximately 4900 blows per minute. In this particular instance, the hammer is operated by compressed air at twenty-five pounds per square inch pressure for about one-fourth second in which twelve to fifteen blows are struck. The air is introduced into the housing 100 (Fig. 5) of the air hammer through the pipe 101. The housing 100 rests on the lower portion of bracket 97 and holds the lower portion of the air hammer 98 which is securely clamped therein by the nut 102. The upper portion of the air hammer 98 is clamped to the bracket 97 by the cap 103 and the anvil 95 rests in an aperture in the end thereof. The hammer 98 is placed in operation by movement of bar 104 (Fig. 1) inward against the pin 105 of the valve 99 (Fig. 5) which moves the piston 106 back in the sleeve 107 allowing the compressed air usually confined in the openings 30 in the pipe 101, the housing 100, the plug 108 and sleeve 107 to pass through the opening 109 in said sleeve 107, the passage between said sleeve 107 and the housing 100, the opening 110 in said sleeve 107, the opening about the pin 105 and the 35 passage 111 in the housing 100 to the air hammer 98. The bar 104 is mounted on the lever 112 (only partially shown) which is moved as required by a cam (not shown) on the main cam shaft below the table 16 and is moved back after the operating interval of the air hammer. The piston 106 is returned to the position shown by the expansion of spring 112.

The wire 10 must be flattened to the order of .0012 inch thickness for it to function properly when sealed into a vitreous body and a swaging action, either hammering or squeezing, such as performed by the air hammer 98 is necessary for proper control of the flattening operation. The differences in hardness and section commonly found in a given length of wire 10 do not materially affect the uniformity of the flattened section produced by such a swaging operation. The air-operated hammer 98 likewise provides additional advantages in that the period of operation and the air pressure applied to the hammer 98 can easily be controlled and adjusted to meet the requirements of the particular wire 10 being flattened. In this instance, the anvils 94 and 95 have inserts 113 and 114 respectively of an 50 extremely hard wear-resistant material produced by the Carboloy Company of Detroit, Michigan, and known as a cemented tungsten carbide. Following the swaging operation, the wedge 115 is inserted between the inserts 113 and 114 to cause them to separate and give free passage for the wire 10 which is then indexed through the guide tube 96 to the cutting apparatus 15. The wedge 115 is slidably mounted in an arm 116 extending from the cap 103 and is operated by the lever 117 which is pivoted on a pin 117' on said cap 103 and engages the bar 104 through the finger 118. The motion of the bar 104 stopping the flow of air to the hammer 98 allows the lever 117 to swing, so that the wedge 115 is 65 carried into position between the inserts 113 and

114 and causes the spring 119, a portion of which is located in a well in the lower end of said lever 117, to expand.

The cutting apparatus 15 (Fig. 1) is comprised essentially of the knife 120 and the circular disc 121 which provides the mating cutting edge. The wire 10 advanced beyond the guide tube 96 passes through an aperture in a plate 122 so as to extend beyond the disc shaped insert 121 and knife 120 a distance equal to the length of the individual leading-in wire desired. The plate 122 is mounted on an arm extending from the bracket 97 and retains the disc 121 in a fixed position, while the knife 120 is mounted on the lever 123 and is moved down thereby to sever the wire 10 when said wire 10 finally comes to rest. The lever 123 is pivoted on the shaft 124 extending from the bracket 97 and is moved at the correct moment by a cam (not shown) located below the table 16 and acting through the rod 125. The wire 126 severed from wire 10 and forming the leading-in wire with the flattened portion 127 is preferably caught in a small tray (not shown) which can be unloaded at suitable intervals.

What we claim as new and desire to secure by Letters Patent of the United States is:

1. Apparatus for flattening portions of a leading-in wire comprising a pair of opposed anvils, means for intermittently feeding a length of the wire longitudinally to carry spaced portions thereof between the faces of said anvils, means operable upon cessation of the longitudinal movement of said wire for repeatedly actuating one of said anvils to compress the portion of the wire therebetween and flatten it to the desired thickness, and means for severing said wire into lengths each including one of said flattened portions.

2. Apparatus for flattening portions of a leading-in wire comprising a pair of opposed anvils, means for intermittently feeding a length of the wire longitudinally to carry spaced portions thereof between the faces of said anvils, pneumatic means operable upon cessation of the longitudinal movement of said wire for repeatedly actuating one of said anvils to compress the portion of the wire therebetween and flatten it to the desired thickness, and means for severing said wire into lengths each including one of said flattened portions.

3. In a device of the type described, the combination of means for feeding a wire longitudinally, means disposed adjacent the path of said wire for scraping off the surface of a portion thereof, a pair of anvils disposed adjacent the path of said wire and adapted to receive said wire therebetween, and means for actuating one of said anvils to strike the previously scraped portion of the said wire a multiplicity of relatively light blows to flatten it.

4. In a device of the type described, the combination of means for feeding a wire longitudinally, means disposed adjacent the path of said wire for scraping off the surface of a portion thereof, a pair of anvils disposed adjacent the path of said wire and adapted to receive said wire therebetween, means for actuating one of said anvils to strike the previously scraped portion of the said wire a multiplicity of relatively light blows to flatten it, and means for severing said wire into lengths each including one of said flattened portions.

5. Apparatus for making leading-in wires comprising means for supporting and moving a wire, a knife mounted adjacent the path of said wire,

means for moving said knife into engagement with said wire, means for revolving said knife around said wire and moving it longitudinally back and forth across the surface of a portion thereof to scrape off the surface of said portion, a pair of anvils located adjacent to the path of said wire and adapted to receive the previously scraped portion of said wire therebetween, means for actuating one of said anvils to strike said wire a multiplicity of relatively light blows to flatten it, and means located adjacent said anvils for severing said wire into lengths each including one of said flattened portions.

6. Apparatus for making leading-in wires comprising means for supporting and moving a wire longitudinally, a knife mounted adjacent the path of said wire, means for moving said knife into engagement with said wire, means for revolving said knife around said wire and moving it longitudinally back and forth across the surface of a portion thereof to scrape off the surface of said portion, jaws located on opposite sides of said knife and adapted to grip and hold the wire during the operating period of the knife so that the portion engaged by it does not move, means for restricting the movement of said knife toward the wire to limit the amount of material scraped therefrom by said knife, a pair of anvils located adjacent to the path of said wire and adapted to

receive the previously scraped portion of said wire therebetween, means for actuating one of said anvils to strike said wire a multiplicity of relatively light blows to flatten it, and means located adjacent said anvils for severing said wire into lengths each including one of said flattened portions. 5

7. In a device of the type described, means for holding a length of wire, and means for scraping off the surface of a portion of said wire comprising 10 a knife arranged to be pressed against said wire, and means for revolving said knife around said wire and moving it longitudinally back and forth across the surface of a portion thereof.

8. In a device of the type described, mechanism 15 for scraping off the surface of a portion of a wire comprising a shaft having a longitudinal groove therein for receiving said wire, a disc rotatably mounted at one end of said shaft, a knife mounted on said disc and arranged to extend across and be 20 pressed against a portion of the wire extending from the said end of said shaft, means for gripping and holding the said portion of said wire, and means on said disc for moving said knife longitudinally back and forth across the surface 25 of a portion of said wire as said knife is revolved about the wire by said disc.
